UNITED STATES PATENT OFFICE.

JOSEPH TREMBLEY, OF ARGYLE, MINNESOTA.

CLAMP FOR HOLDING MEAT.

No. 822,166.

Specification of Letters Patent.

Patented May 29, 1906.

Application filed October 7, 1905. Serial No. 281,806.

To all whom it may concern:

Be it known that I, JOSEPH TREMBLEY, a citizen of the United States, residing at Argyle, in the county of Marshall and State of Minnesota, have invented new and useful Improvements in Clamps for Holding Meat, of which the following is a specification.

My invention relates to clamps for holding meat in position while it is being cut or the bone thereof being sawed; and its primary object is to provide a novel and highly-useful device of this character which is comparatively simple and durable and cheap to manufacture.

With the above and other objects in view the invention consists in the construction, combination, and arrangement of parts hereinafter fully described, claimed, and illustrated in the accompanying drawings, where-

20 in—

Figure 1 is a detailed perspective view of a butcher's block having my improved meat-clamp secured thereto. Fig. 2 is a detailed side elevation of the plunger. Fig. 3 is a detailed rear elevation of the standard. Fig. 4 is a detailed side elevation of the clamping-arm.

Referring to the drawings by reference-numerals, 1 designates a butcher's chopping-block supported by means of legs 2, the same being of the usual form and construction.

A standard 3 is secured to the block 1 and rises vertically above the working face thereof and is provided with a horizontal arm 4, which extends laterally over the working face of the block to a point adjacent its center. The lower end of the standard 3 is flattened to provide an attaching member 5, having openings 6, through which may be let suitable fastening means to secure the standard in applied position. The end of the arms 4 is provided with an opening (not shown) and intermediate its ends with a vertically-disposed bearing 9. Pivots mounted upon the standard 3, as at 10, is a clamping-arm 11, the same having its free end provided with a plurality of meat-engaging fingers 12, said fingers being spaced and disposed horizontally, then downwardly, and having the downwardly-disposed portions thereof pointed whereby to facilitate the engagement of the meat thereby. The lever 11 is bent at a point intermediate its ends and is provided at this bent portion with an elongated opening 13, whereby said opening is arranged on the arc of the circle. A plunger

15 is slidably mounted within the bearing 9 and has its lower end bifurcated to straddle the lever 11, the legs 16 of said bifurcation being provided with aligned openings 17, through which projects a bolt 18 to engage in the slot 13, whereby to connect the plunger with the lever and to permit the latter to have a limited relative movement thereon. The plunger 15 is provided at a point adjacent its upper end with a shoulder 19, and interposed between the said shoulder and bearing 9 is an expansion-spring 20, the same serving to retain the fingered end of the lever 11 elevated from the working face of the block 1. An operating-lever 21 has one end secured to the horizontal arm 4 by means of links 22, secured to one end of the lever and to the end of the arm 4. The operating-lever 21 is curved from a point adjacent its pivoted end to the handle portion 23 thereof on the arc of the circle of which the bearing 9 is the center. The curved portion of the operating-lever is adapted to fit in the upper bifurcated end 24 of the plunger 15, whereby the downward movement of the operating-lever will cause the plunger to descend and bring the fingers 12 of the clamping-lever 11 in engagement with a piece of meat. The elongated opening 13 compensates for the immovable pivot of the lever 11 upon the standard 3. Immediately upon the removal of the pressure from the operating-lever 21 the spring will move the plunger 15 upward, and thereby extract the fingers 12 from engagement with the meat and retain them in elevated position. A ratchet 24' is secured to the standard 3 and rises vertically above the arm 4. The operating-lever 21 is provided with a ratchet 25, which is adapted to engage one of the teeth of the bar 24 to retain the fingers 12 in engagement with a piece of meat, and thereby clamp the meat between the same and the working face of the block 1. The operation of this improved meat-clamp may be stated in the following:

When it is desired to clamp a piece of meat down upon the working face of the block 1, the operating-lever 21 is caused to move downward through the medium of the handle 23, and in view of the interposition of the plunger 15 between the operating-lever 21 and the clamping-lever 11 the latter-named lever is also caused to move downward and bring the fingers 12 into engagement with a piece of meat and clamp the same upon the working face of the block 1. To retain the

meat clamped, the ratchet 25 is thrown into engagement with one of the teeth of the bar 24. When it is desired to release the meat, the ratchet 25 is thrown out of engagement 5 with the tooth and the spring 20 will move the plunger 15 upward. The upward movement of the plunger 15 will elevate the lever 11, and consequently extract the fingers 12 from the meat and relieve the pressure thereon.

10 Having fully described and illustrated my invention, what I claim is—

1. In a device of the character described, the combination with a butcher's chopping-block, of a standard secured thereto, said 15 standard being provided with a horizontally-disposed arm extending across the working face of the block, a clamping-lever pivotally secured to the standard, a plunger movably mounted upon the horizontal arm and having connection with the clamping-lever, a lever pivotally secured to the horizontal arm and adapted to engage the plunger, and a spring carried by the plunger and serving to retain the clamping-arm normally elevated.
- 25 2. In a device of the character described, the combination with a butcher's chopping-block, of a standard secured thereto, said standard being provided with a horizontally-disposed arm extending above the working 30 face of the block and provided with a bearing,

a clamping-lever pivotally secured to the standard and having its free end provided with fingers, said lever being provided with a curved and elongated slot, a plunger movably mounted in said bearing, means passing 35 through said slot and engaging the plunger to provide a loose connection therebetween, a rack-bar secured to the standard, a lever pivotally mounted upon the horizontal arm and provided with a curved portion adapted to 40 engage the plunger, and a ratchet carried by said operating-lever and adapted to engage one of the teeth of the said bar.

3. In a device of the character described, the combination with a butcher's block, of a 45 standard secured thereto, a clamping-arm pivotally secured to the standard and provided with a curved elongated opening, a movably-mounted plunger, means passing through said opening and engaging the plunger to provide a loose connection therebetween, and a pivotally-mounted operating-lever having a curved portion adapted to engage said plunger.

In testimony whereof I affix my signature 55 in presence of two witnesses.

JOSEPH TREMBLEY.
